DECODING APPARATUS

Norman F. Agnew, Penn Township, Allegheny County, Pa., assignor to The Union Switch & Signal Company, Swissvale, Pa., a corporation of Pennsylvania

Application February 25, 1941, Serial No. 380,415

9 Claims. (Cl. 246—34)

My invention relates to decoding apparatus, and it has particular reference to the provision of apparatus of the class which enables codes of the time code type to be decoded by a group of relays. More particularly, my invention has reference to the provision of apparatus for use in coded railway signal systems, and which apparatus is effective to decode time codes by measuring the duration of the cycles of such codes.

An object of my invention is to provide novel and improved apparatus for decoding codes which are differentiated from one another by the relative lengths or durations of the individual code cycles comprising such codes.

Another object is to provide novel and improved apparatus for decoding codes comprising recurrent cycles each consisting of one "on" and one "off" interval during which energy does and does not flow respectively, and which codes differ from one another by being comprised of individual code cycles which have different durations.

An additional object is to provide novel and improved apparatus for differentiating codes in accordance with the relative durations of the individual code cycles comprising such codes, irrespective of the relative durations of the "on" and "off" intervals comprising such codes.

A further object is to provide novel and improved decoding apparatus for differentiating codes in accordance with the relative durations of the individual code cycles comprising such codes irrespective of the relative durations of the "on" intervals of the different code cycles comprising such codes.

Another object is to provide novel and improved apparatus for decoding codes by a group of timing relays.

An additional object is to provide novel and improved decoding apparatus having a code responsive device operated from one position to another in response to each "on" interval of a code, and incorporating means rendered effective by such device in its other position for maintaining the device in such other position for a given interval of time irrespective of the duration of the "on" intervals of the code cycles constituting such codes.

The above-mentioned and other important objects and characteristic features of my invention which will become readily apparent from the following description, are attained in accordance with my invention by utilizing a code following device operated from one position to another upon receipt of an "on" interval of code energy, 55

by providing means rendered effective when the device reaches its other position for maintaining the device in such position for a given interval irrespective of the duration of the "on" interval of energy actuating the device, and by providing decoding relays which measure the time interval intervening between said given interval and the next succeeding "on" interval of the code. In accordance with the duration of the measured time interval, the decoding relays are selectively actuated or controlled and selective controls are established according to the duration of the measured time interval.

My invention also resides in the arrangement of apparatus into novel decoding systems and in the incorporation of such decoding apparatus in railway signal systems, as will be pointed out hereinafter.

I shall describe a preferred form of apparatus embodying my invention, and shall then point out the novel features thereof in claims.

In the accompanying drawing, Fig. 1 is a diagrammatic view illustrating one form of apparatus embodying my invention incorporated into a signal system provided for a stretch of railway track. Fig. 2 is a chart or diagrammatic time table of the sequence of operation of the relays shown in Fig. 1 under the several different conditions of code employed. Fig. 3 is a diagrammatic key to the symbols employed in Fig. 2.

Referring to Fig. 1, the reference character X designates a stretch of railway track over which traffic normally moves in the eastbound direction, or from left to right as viewed in the drawing, and which stretch is provided with a signal system incorporating novel decoding apparatus embodying my invention. In accordance with the usual practice, the rails 1 and 1a of the stretch are divided by insulated joints 2 into a plurality of successive adjoining track sections, of which only one section, D—E, is represented complete in the drawing.

Each of the sections of track X is provided adjacent its entrance end with a signal, designated by the reference character S with a suitably distinguishing suffix, for governing traffic in the normal direction of traffic movement. The signals S may be of any suitable form, such as semaphore, searchlight, position light, etc., but for the purposes of the following description it will be assumed that the signals are of the color light type comprising a plurality of lamps. Signal SD, for example, comprises four lamps 6, 7, 8 and 9. These lamps are adapted to be selec-

tively energized and may be utilized for controlling traffic on stretch X in a manner to be made clear presently.

The rails of section D—E are incorporated into a track circuit which comprises, in addition to the track rails, a track relay TRD connected to the rails at the entrance end D of the section and suitable trackway energy transmitting apparatus located at the exit end E of the section for supplying energy to the track circuit. The trackway energy supplying means for each section comprises a suitable source of current, which may be either a source of unidirectional current or a source of alternating current; a code or impulse generating means for generating codes comprising recurrent cycles each consisting of an "on" interval and an "off" interval during which energy does and does not flow respectively; and suitable means for selecting the particular one of such codes for transmission through the track circuit in accordance with traffic conditions in advance.

These trackway energy supplying means are arranged to provide the associated track circuit with one or another of a plurality of codes each comprising recurrent code cycles which are differentiated from one another by the relative durations or lengths of such cycles. Each code cycle comprises an "on" interval followed by an "off" interval, and, as will be readily apparent hereinafter, the decoding apparatus embodying my invention is adapted to decode such codes in accordance with the relative durations of the code cycles comprising such codes irrespective of the relative durations of the "on" and "off" intervals comprising such cycles. That is to say, the decoding apparatus embodying my invention functions to decode codes comprising cycles varying in duration but not shorter in duration than a given interval, hereinafter mentioned, and the "on" and "off" intervals of such cycles may have any relative proportion provided that the "on" intervals of such cycles do not exceed the given interval. Thus, for example, the codes may comprise cycles each having "on" intervals equal in duration, followed by "off" intervals which have different durations for different codes so as to provide code cycles having different durations. The "on" intervals of code in such case may be of relatively short duration separated from each other by "off" periods or intervals varying in duration, similar, for example, to the impulse type codes shown and described in United States Letters Patent No. 2,197,414, granted on April 16, 1940, to Willard P. Place, for Signal systems; or such "on" intervals may be of relatively long duration separated from each other by relatively short "off" periods varying in duration. On the other hand, the "on" intervals of the different codes may be of different durations separated from each other by "off" intervals of equal duration; or the cycles may be comprised of "on" and "off" intervals having durations equal for a given code but differing for different codes. It follows, therefore, that the different codes may be comprised of "on" and "off" intervals having any relative proportion provided that the durations of the code cycles differ for different codes but do not have a duration shorter than the given interval previously mentioned, and that the durations of the "on" intervals of such codes do not exceed such given interval.

A typical arrangement of apparatus for supplying trackway energy to the track sections of stretch X is represented in the drawing adjacent the exit end D of the section next in the rear or

extending to the left as viewed in the drawing, from section D—E. In the particular arrangement illustrated, a direct current source such as a battery not shown but having its terminals designated by the reference characters B and C, is represented as supplying "on" impulses of relatively short duration to the track rails through the medium of impulse generating means. These means comprise a track transformer, designated by the reference character TT with a distinguishing suffix, which has its secondary winding 10 connected to the track rails at the exit end of the associated section, and which transformer has its primary winding 11 connected in multiple with a condenser 13 and supplied with unidirectional current from the source periodically interrupted or coded through the medium of suitable interrupting or code transmitting apparatus. The code transmitting apparatus may be of any desired type, and as shown comprises a plurality of code transmitters or coders, designated by the reference character CT with a suitably distinguishing suffix, each operating a contact member 12 at a different rate. For the purposes of the present description, I shall assume that coders CT75, CT52 and CT40 operate their associated contact members 12 at the rate of 75, 52 and 40 times per minute, respectively. It follows that a contact member 12 of a coder, when interposed in a circuit supplied with energy, periodically interrupts or codes such energy at the rate of 75, 52 or 40 times per minute, and that such coding comprises recurrent cycles each consisting of an "on" interval of current flow when the contact member of the code transmitter is in its upper or closed position, followed by an "off" interval during which no current flows when the contact member of the coder is in its released or opened position. It is also apparent that the 75, 52 and 40 codes are differentiated from one another by the relative lengths or durations of the individual code cycles comprising such codes.

For the purpose of more clearly defining my invention, I shall refer hereinafter to cycle units, and I shall assume that 60 cycle units equal one second. The code cycles of the 75 code, for example, have a duration of $\frac{1}{75}$ of a second and thus may be expressed as having a duration of 48 cycle units; the code cycles of the 52 code have a duration of 69 cycle units; while the code cycles of the 40 code have a duration of 90 cycle units.

Each contact member 12 of the coders CT is interposed in one or another of a plurality of circuits, shortly to be traced, each of which includes the primary winding 11 of transformer TTD and condenser 13 connected in multiple therewith. It follows that each time the direct current source is connected to transformer TTD through a contact member 12 of a coder CT, energy is stored in the circuit of the transformer and condenser, and each time such contact opens, the stored energy rapidly collapses and causes to flow in the track circuit a relatively short impulse of energy. These "on" impulses of energy in the track rails are of substantially the same relative duration irrespective of the rate of operation of the coder contact member 12 over which energy is supplied to the transformer and condenser, but the durations of the "off" intervals when no energy is applied to the track rails will of course vary in accordance with the particular contact member 12 employed, hence these contacts function to differentiate the codes by varying the durations of the code cycles which

may be considered as comprising the interval between successive openings of a coder contact member 12.

The impulses of energy applied to section D—E by the trackway energy transmitting apparatus at the exit end E of the section, which apparatus is not shown in the drawing but which substantially corresponds to the apparatus represented provided at D and heretofore described, are received by code following track relay TRD when the section is unoccupied. Relay TRD picks up in response to each "on" interval of energy in the track rails, to actuate decoding apparatus effective to differentiate between the codes in the track by measuring the relative durations of the cycles constituting such codes.

The decoding apparatus comprises a code responsive device or relay M; a plurality of interval measuring devices one for measuring a first interval of time equal in duration to the here-tofore mentioned given interval and the others for measuring other intervals of time; and a group of code registering relays for detecting and registering the relative durations of the cycles of codes in the track.

The interval measuring devices, as shown, comprise slow acting relays 1R, 2R, AR and BR. Relays 1R and 2R are energized over an easily traced circuit which extends from terminal B through back contact 15 of relay M, back contact 16 of relay 1R, and the windings of relays 1R and 2R in multiple to terminal C. Relay 2R when picked up closes its front contact 17 to close a stick circuit path connected in multiple with back contact 16 of relay 1R, so that relays 2R and 1R are maintained energized over this stick circuit path after relay 1R picks up. Relay 1R is proportioned to be slightly slower in picking up than relay 2R, thereby enabling the latter relay to close its front contact 17 and complete the previously mentioned stick circuit path prior to relay 1R opening its back contact 16. Both relays 1R and 2R are represented as having asymmetrical units 18 connected, in opposition to the flow of current energizing such relays, across their respective terminals to assist in providing such relays with slow release characteristics. Relay 1R is proportioned to have a slow release period shorter in duration than relay 2R, and to correspond with the heretofore assumed 75, 52 and 40 code rates, which comprise code cycles having durations of 48, 69 and 90 cycle units, respectively, relay 1R preferably has a slow release period of 20 cycle units. Relay 2R is proportioned to have a slow release interval longer in duration than the duration of the "on" interval of any of the codes, but shorter than the duration of any of the cycles comprising such codes. The given interval measured by the slow release period of relay 2R may, for example, have a duration of 36 cycle units. This interval is, of course, shorter in duration than the shortest cycle of code employed i. e. 48 cycle units.

Relay AR is energized over a pick-up circuit extending from terminal B through front contact 15 of relay M, front contact 19 of relay 2R, back contact 20 of relay 1R and the winding of relay AR to terminal C, and this relay is provided with a stick circuit path in which its front contact 21 shunts back contact 20 of relay 1R in the just traced pick-up circuit for relay AR. Relay BR is provided with a pick-up circuit including front contact 22 of relay AR and the upper winding of relay BR, and this relay is provided with a stick circuit which passes from ter-

5 minal B through front contact 15 of relay M, front contact 19 of relay 2R, front contact 23 of relay BR and the lower winding of relay BR to terminal C. Each relay AR and BR is provided with an asymmetrical unit 18 connected across its terminals to aid in providing such relay with slow release characteristics. Relay AR is proportioned to have a slow release period at least as long in duration as the difference (12 cycle units) between the release period of relay 2R (36 cycle units) and the length (48 cycle units) of the shortest code cycle employed, but shorter in duration than the difference (33 cycle units) between the release period of relay 2R and the length (69 cycle units) of the second shortest code cycle employed. For convenience, relay AR will be assumed in the following description to have a release interval of, say, 22 cycle units. Relay BR is proportioned to have a release period sufficient so that the release periods of relays AR and BR, taken successively, have a duration longer than the difference (33 cycle units) between the release period of relay 2R and the second shortest code cycle employed, but which duration is shorter than the difference (54 cycle units) between the duration of the release period of relay 2R and the length (90 cycle units) of the longest code cycle employed. The release period of relay BR thus will vary in accordance with the release interval selected for relay AR, and for the purposes of this description it will be assumed that relay BR has a release period of 22 cycle units.

35 The code registering relays are designated by the reference characters FA, ME and SL, respectively. Relay FA is provided with an energizing circuit extending from terminal B through front contact 15 of relay M, front contact 19 of relay 2R, front contact 20 of relay 1R, front contact 24 of relay AR and the winding of relay FA to terminal C; and the relay preferably is provided with slow releasing characteristics sufficient, at least, to hold the relay in its picked-up position for an interval equal to the difference (28 cycle units) between the release period (20 cycle units) of relay 1R and the length (48 cycle units) of the shortest code cycle employed. Relay ME is provided with an energizing circuit passing from terminal B through front contact 15 of relay M, front contact 19 of relay 2R, front contact 20 of relay 1R, back contact 24 of relay AR, front contact 25 of relay BR, and the winding of relay ME to terminal C; and this relay preferably has a slow release interval equal in duration to the difference (49 cycle units) between the release period of relay 1R and the length (69 cycle units) of the second shortest code cycle employed. Relay SL is energized over a circuit which substantially corresponds to the circuit of relay ME except that back contact 25 of relay BR and the winding of relay SL replace respectively front contact 25 of relay BR and the winding of relay ME. Relay SL preferably is provided with a slow release period which enables the relay to bridge the difference (70 cycle units) between the release period of relay 1R and the length (90 cycle units) of the longest code cycle employed.

70 The code registering relays FA, ME and SL cooperate in controlling signal SD in the following manner: When all of the code registering relays are released, as shown, lamp 9 of signal SD is energized over a circuit extending from terminal B through back contact 26 of relay FA, back contact 27 of relay ME, back contact 28 of

relay SL and the filament of lamp 9 to terminal C. The illumination of lamp 9 may be employed as the most restrictive indication of the signal, indicating for example that the associated section is occupied. When relay SL is picked up and relays FA and ME are released, lamp 8 of signal SD is illuminated over a circuit extending from terminal B through back contact 26 of relay FA, back contact 27 of relay ME, front contact 28 of relay SL and the filament of lamp 8 to terminal C. The illumination of lamp 8 may be employed as an indication less restrictive than that of lamp 9 but more restrictive than that of any other lamp. When relay ME is picked up but relay FA is released, lamp 7 is illuminated over an obvious circuit including back contact 26 of relay FA and front contact 27 of relay ME, and the illumination of such lamp may be employed as an indication less restrictive than those of lamps 8 and 9 but more restrictive than that of any other lamp. When relay FA is picked up, lamp 6 is energized over an obvious circuit including front contact 26 of relay FA, and the illumination of this lamp may be utilized as the least restrictive indication of the signal.

The code registering relays further cooperate in controlling the supply of trackway energy to the section next in the rear of section D—E. When all code registering relays are released, as shown in the drawing, the section in the rear of section D—E is supplied with 40 code energy over a circuit which extends from terminal B through back contact 29 of relay FA, back contact 30 of relay ME, back contact 31 of relay SL, contact 12 of coder CT40, primary winding 11 of transformer TTD and condenser 13 in parallel, to terminal C. When however relay SL is energized and relays FA and ME are de-energized, the section in the rear of section D—E is supplied with 52 code energy over a circuit which extends from terminal B through back contact 29 of relay FA, back contact 30 of relay ME, front contact 31 of relay SL, contact 12 of coder CT52 and primary winding 11 of transformer TTD in multiple with condenser 13, to terminal C. Whenever relay FA is picked up to close its front contact 29, or relay FA is released to close its back contact 29 and relay ME is picked up to close its front contact 30, the section in the rear of section D—E is supplied with 75 code energy over a circuit which includes contact 12 of coder CT75.

The above-mentioned controls of signal SD and of the energy supplied to the section in the rear of section D—E are effected in the following manner by the decoding apparatus differentiating the different code rates of energy applied to the section.

When section D—E is occupied by a train, such as train W represented in the drawing, the coded energy applied at E to the section is shunted by the train away from relay TRD, and as a result relay TRD is inactive and its front contact 33 is held steadily open. Relays M, AR, BR, FA, ME and SL are released, but relays 1R and 2R are energized since back contact 15 of relay M is steadily closed. Lamp 9 of signal SD is energized, and the previously traced circuit over which 40 code is supplied to the rear section is completed. The section next in the rear of an occupied section is, therefore, supplied with 40 code energy.

When the train vacates section D—E and occupies the section next in advance, section D—E

is supplied with 40 code energy. Relay TRD of course responds to such coded energy and closes its front contact 33 each time an "on" impulse of energy is in the track rails. When relay TRD closes its front contact 33 in response to the first "on" impulse of 40 code energy received in the rails of section D—E, relay M is picked up and closes its front contact 34 to complete an obvious stick circuit which includes front contact 35 of relay 2R. Relay M also opens its back contact 15 to deenergize relays 1R and 2R, but such relays remain up for their respective slow release intervals. Relay SL is now energized over its previously traced circuit, and picks up to shift the coding of current supplied to the rear section from the 40 to the 52 code rate; and also to shift the energization of the lamps of signal SD from lamp 9 to lamp 8.

Relay 1R drops at the end of its slow release interval or 20 cycle units after relay M picks up, and front contact 20 of relay 1R opens to deenergize relay SL while back contact 20 of relay 1R closes to energize relay AR. Relay AR accordingly picks up to close its front contact 22, whereupon relay BR also picks up, and front contacts 21 and 23 of relays AR and BR are closed to complete respectively the stick circuits of such relays. Relay 2R next releases at the end of its slow release interval (36 cycle units after relay M picks up or 16 cycle units after relay 1R releases), and opens its front contact 19 interposed in the stick circuit of relays AR and BR. In addition, relay 2R opens its front contact 35 interposed in the stick circuit of relay M, and since it has been assumed that the release interval of relay 2R exceeds the duration of the "on" interval of any of the codes, relay TRD is at this time released so that relay M is deenergized and releases. With relays M and 1R released, relay 2R first picks up, and then relay 1R picks up, and these two relays are held up over back contact 15 of relay M until relay TRD responds to the next succeeding "on" interval of energy received from the section. Relays AR and BR, however, release prior to relay TRD responding to the next succeeding "on" impulse of the 40 code, so that when relay TRD picks up in response to such "on" impulse to reenergize relay M, relay SL is again energized. The slow release interval of relay SL, as mentioned heretofore, is selected to hold such relay up for an interval (70 cycle units) substantially equal to the difference in duration between the length of the longest code cycle and the release period of relay 1R. With relays M and SL energized and relays 1R and 2R deenergized, the apparatus repeats the cycle of operation previously described, and this operation is, of course, repeated each time an "on" interval of 40 code energy is received by relay TRD from the track rails.

When section D—E and the section next in advance are unoccupied, and the second section in advance of section D—E is occupied, 52 code energy is supplied to section D—E. The cycles comprising this code each have a duration of 69 cycle units, hence when the coded energy supplied to section D—E is shifted from the 40 to the 52 code, the first "on" interval of such energy actuates relay TRD to pick up relay M, prior to relay BR releasing at the end of its slow release interval but after relay AR releases. With relays 1R, 2R and BR picked up when relay M picks up, relay ME is energized but relay SL is deenergized. The coded energy supplied to the section in the rear of section D—E is accordingly shifted from the 52 to the 75 code rate, and the energization of the

lamps of signal SD is shifted from lamp 8 to lamp 7.

Relay BR is energized over its stick circuit when relay M picks up prior to contact 23 of relay BR opening, and the latter relay is held energized over this circuit until after relay 1R drops to pick up relay AR and thus complete the pick-up circuit of relay BR. Relay AR becomes deenergized when relays M and 2R drop at the end of the slow release interval of relay 2R, and, as pointed out heretofore, the slow release interval of relay AR is selected so that relay AR releases prior to relay M being picked up in response to relay TRD responding to the next successive "on" interval of the 52 code. Relay BR of course becomes deenergized only after relay AR releases, and the slow release period of relay BR is effective to hold that relay picked up so that its front contacts 23 and 25 are closed, until relay TRD responds to the next succeeding "on" impulse of coded energy, and relay M accordingly picks up to complete the previously mentioned stick circuit of relay BR and the previously mentioned energizing circuit of relay ME. The slow release period of relay ME is selected so as to enable that relay to bridge the interval (49 cycle units) intervening between the releasing of relay 1R and the picking up of relay M in response to relay TRD being actuated by the next succeeding "on" interval of the 52 code. The above described operation of the apparatus is, of course, cyclically repeated as long as 52 code energy is received by relay TRD from the track rails.

When section D—E and at least the two sections immediately in advance of that section are unoccupied, section D—E is supplied with 75 code energy which as pointed out heretofore, is comprised of code cycles each having a duration of 48 cycle units. It is readily apparent therefore that when the coded energy in section D—E is shifted from the 52 to the 75 code rate, relay TRD is actuated by the first "on" impulse of the 75 code prior to relay AR releasing, so that when relay M picks up it completes the previously traced circuit of relay FA through front contacts of relays M, 1R, 2R, AR and BR. Relays 1R and 2R are deenergized when relay M picks up, relay FA is deenergized when relay 1R drops at the end of its slow release period, relay AR is energized until relay 2R drops at the end of its slow release period, while relay BR remains energized since relay M is caused to pick up due to relay TRD following 75 code energy, prior to relay AR dropping, and when relay M picks up relays FA, AR and BR are reenergized. Relays FA and AR are provided with slow release characteristics selected to maintain such relays in their respective picked-up positions during the intervals that they are deenergized when relay TRD follows 75 code. It follows, therefore, that relays FA, AR and BR are maintained in their respective picked-up positions in response to 75 code energy and that the decoding apparatus embodying my invention cyclically repeats the operation just described as long as 75 code energy is received by relay TRD from the rails of the section.

It is, of course, readily apparent that when relay FA is selected for energization, lamp 6 of signal SD is energized while lamp 7 is deenergized, and also that 75 code energy is supplied to the section in the rear section D—E.

As a convenient reference, a time table of the energization of all of the relays is shown in Fig. 2 and the key to the symbols used in this time

table is shown in Fig. 3. From an inspection of these two figures, it can readily be ascertained when the coil circuit of any relay is closed, when the relay picks up its front contacts, when its coil circuit is opened and when its front contacts are released.

Although I have herein shown and described only one form of decoding apparatus embodying my invention, it is understood that various changes and modifications may be made therein within the scope of the appended claims without departing from the spirit and scope of my invention.

Having thus described my invention, what I claim is:

1. In combination with a control circuit supplied with one or another of a plurality of codes each comprising recurrent code cycles consisting of an "on" interval followed by an "off" interval during which energy does and does not flow respectively, said "on" intervals of the different codes each being not longer in duration than a given interval of time and said codes differing from each other in the relative durations of the code cycles, means operable by energy received from said circuit for picking up a relay in response to each "on" interval of energy in said circuit, other means operable upon receipt of an "on" interval of energy for maintaining such relay energized for said given interval regardless of the duration of the received "on" interval of energy, and decoding means controlled by said relay and selectively responsive to the relative durations of the code cycles of such codes.

2. In combination with a stretch of railway track supplied with one or another of a plurality of codes each comprising recurrent code cycles consisting of an "on" interval followed by an "off" interval during which energy does and does not flow respectively, said "on" intervals of the different codes each being not longer in duration than a given interval of time and said codes differing from each other in the relative durations of the code cycles, means operable by energy received from the rails of said stretch for picking up a relay in response to each "on" interval of energy in the rails, other means operable upon receipt of an "on" interval of energy for maintaining said relay energized for said given interval regardless of the duration of the received "on" interval of energy, and decoding means controlled jointly by said relay and by said other means and selectively responsive to the relative durations of the code cycles of said code.

3. In combination with a stretch of railway track supplied with one or another of a plurality of codes each comprising an "on" interval of current flow not longer in duration than a given interval and an "off" interval having one or another of a plurality of durations, a code following relay receiving energy from the rails, means operated by said relay in response to a receipt of an "on" interval of current, other means effective upon operation of said first means for maintaining said first means operated for said given interval regardless of the length of said "on" interval of current, and decoding means controlled jointly by said first means and said second means and selectively responsive to the durations of the "off" intervals between successive "on" intervals of the different codes.

4. In combination with a stretch of railway track supplied with one or another of a plurality of codes each comprised of cycles consisting of an "on" interval of energy not longer in duration

than a given interval and an "off" interval having one or another of a plurality of durations, a relay operated in response to each energy impulse in the rails, means operable upon operation of said relay for maintaining said relay operated for said given interval regardless of the length of said "on" interval, and decoding means controlled jointly by said relay and by said first-mentioned means and selectively responsive to the relative durations of the "off" intervals of the cycles constituting said codes.

5. In combination with a stretch of railway track supplied with one or another of a plurality of codes each comprising recurrent code cycles consisting of an "on" interval followed by an "off" interval during which energy does and does not flow respectively, said "on" intervals of the different codes each being not longer in duration than a given interval of time and said codes differing from each other in the relative durations of the comprised code cycles, a first relay, means operable by energy received from the rails of said stretch for picking up said relay in response to each "on" interval of energy in the rails, a second relay energized over a back contact of said first relay and having a slow release period equal in duration to said given interval, means controlled by said second relay for maintaining said first relay energized for said given interval regardless of the relative durations of the received "on" intervals of energy, and decoding means controlled jointly by said first relay and by said second relay and selectively responsive to the relative durations of the code cycles of said codes.

6. In combination with a control circuit supplied with one or another of a plurality of codes each comprising recurrent code cycles consisting of an "on" interval followed by an "off" interval during which energy does and does not flow respectively, said "on" intervals of the different codes being not longer in duration than a given interval of time and said codes differing from each other in the relative durations of the comprised code cycles, a first relay, means operable by energy received from said control circuit for picking up said relay in response to each "on" interval of energy in said circuit, a second relay energized over a back contact of said first relay and having a slow release interval equal in duration to said given interval, means rendered effective when said first relay picks up and controlled by said second relay for maintaining said first relay energized for said given interval regardless of the relative durations of the received "on" intervals of current from said circuit, a third relay energized over a back contact of said first relay and having a slow release period shorter in duration than said second relay, and decoding means controlled jointly by said first and second and third relays and selectively responsive to the relative durations of the code cycles of said codes.

7. In combination with a stretch of railway track supplied with one or another of a plurality of codes each comprising recurrent code cycles consisting of an "on" interval followed by an "off" interval during which energy does and does not flow respectively, said "on" intervals of the different codes each being not longer in duration than a given interval of time and said codes differing from each other in the relative durations of the comprised code cycles, a first relay, means operable by energy received from the rails of said stretch for picking up said relay in response to each "on" interval of energy in the

rails, a second relay and a third relay, said second relay having a slow release interval equal in duration to said given interval and said third relay having a release interval shorter in duration than said given interval, an energizing circuit for said second relay including a back contact of said first relay and a back contact of said third relay in series, another energizing circuit for said second relay including a back contact of said first relay, a front contact of said second and third relays in multiple, means rendered effective when said first relay picks up and controlled by said second relay for maintaining said first relay energized for said given interval regardless of the relative durations of the "on" intervals of energy received from said rails, and decoding means controlled by said first and second and third relays and selectively responsive to the relative durations of the code cycles comprising said codes.

8. In combination with a control circuit supplied with one or another of a plurality of codes each comprising recurrent code cycles consisting of an "on" interval followed by an "off" interval during which energy does and does not flow respectively, said "on" intervals of the different codes each being not longer in duration than a given interval of time and said codes differing from each other in the relative durations of the comprised code cycles, a first relay, means operable by energy received from said circuit for picking up said relay in response to each "on" interval of energy in said circuit, a second relay and a third relay each energized over a back contact of said first relay, said second relay having a slow release period equal in duration to said given interval of time and said third relay having a slow release period shorter than said second relay, means effective when said first relay picks up and controlled by said second relay for maintaining said first relay energized for said given interval regardless of the relative durations of the received "on" intervals of current, a fourth relay having a pick-up circuit including a front contact of said first relay, a front contact of said second relay and a back contact of said third relay and provided with a stick circuit including a front contact of said second relay, said fourth slow release relay having a slow release interval shorter in duration than the difference in duration between the longest and the shortest code cycle supplied to said circuit, a fifth relay having a pick-up circuit including a front contact of said fourth relay and a stick circuit including a front contact of said second relay and also having a slow release interval, and a plurality of decoding relays controlled by said first, second, third, fourth and fifth relays and selectively energized in accordance with the relative durations of the code cycles comprising said codes.

9. In combination with a stretch of railway track divided into a plurality of successive adjoining track sections, a signal for each section, means for supplying the rails of each of said sections with energy coded at one or another of a plurality of codes each comprising recurrent code cycles consisting of an "on" interval followed by an "off" interval during which energy does and does not flow respectively, said "on" intervals of the different codes each being not longer in duration than a given interval of time and said codes differing from each other in the relative durations of the comprised code cycles, a first relay for each section, means operable by energy received from the rails of the associated section

for picking up the said first relay of that section in response to each "on" interval of energy in the associated section, other means for each section operable upon receipt of an "on" interval of current from the rails of the associated section for maintaining said first relay energized for said given interval regardless of the relative durations of the received "on" intervals of current, decoding means for each section controlled by the as-

sociated relay and by said other means and selectively responsive to the relative durations of the code cycles of said codes, and means controlled by said decoding means for controlling the associated signal and for controlling the supply of current to the section next in the rear of said associated section.
